UNITED STATES PATENT OFFICE.

GEORGE L. SCOTT, OF SHAWNEE, OKLAHOMA.

BRAKE HEAD AND SHOE.

Original application filed January 3, 1920, Serial No. 349,182. Divided and this application filed July 27, 1921, Serial No. 487,963.

To all whom it may concern:

Be it known that I, GEORGE L. SCOTT, citizen of the United States, residing at Shawnee, in the county of Pottawatomie and 5 State of Oklahoma, have invented certain new and useful Improvements in Brake Heads and Shoes, of which the following is a specification.

This invention relates to an improved 10 brake head and shoe, being a division of my application for car brake, filed January 3, 1920, Serial No. 349,182, now Patent No. 1,397,059, and seeks, among other objects, to provide a construction wherein the 15 brake shoe will be firmly locked upon the head but wherein said shoe may be readily removed so that the shoe can be easily renewed.

Other and incidental objects will appear 20 hereinafter.

In the drawing:

Figure 1 is a detail elevation showing the brake head and shoe in connection with a hanger therefor as exemplified in my patent referred to.

Figure 2 is a detail perspective view of the brake head and shoe as well as the hanger, the shoe being detached from the head, and

Figure 3 is a longitudinal sectional view taken through the brake head and shoe.

Referring now more particularly to the drawing, I have, in order to clearly bring out the mounting and operation of my improved brake head and shoe, shown the invention in connection with associated parts of a car brake, as illustrated in my patent previously identified. A car axle is illustrated at 10 and the wheel at the adjacent 35 end of the axle at 11. Journaling the axle is a journal box 12 to which is connected one of the bars 13 of the side frame. Secured to said bar is a hanger bracket 14 upon which is pivoted a brake hanger 15 normally held elevated by a spring 16 and connected with the hanger is a chain 17 by which the hanger may be swung downwardly, it being observed in this connection that the hanger extends over the wheel 11. All 50 of this structure is disclosed in my Patent No. 1,397,059 and is accordingly described only generally herein.

In carrying out the present invention, I employ a brake head 36. As shown in Figure 2, the outer end of the hanger is squared

and the brake head is fitted over the squared end of the hanger and is secured by a cotter pin or other appropriate means. Adjacent one end thereof, the brake head is formed with a transverse opening 37 and entering through the lower face of the head to intersect this opening is a recess 38. Formed in the head at its opposite end is a longitudinally extending recess 39 entering through the adjacent end wall of the head. Fitting the curved lower side of the head is a brake shoe 40 provided at its ends with upstanding flanges 41 adapted to coact with the end walls of the head. At one end thereof, the shoe is provided with an upstanding longitudinally directed hook 42 which engages in the recess 39, the shank of the hook being received in suitable notches in the adjacent end wall of the head, and upstanding from the shoe near its opposite end is a staple 43 which is received within the recess 38. Extending through the opening 37 to be received through the staple 43 is a bolt 44 locking the shoe upon the head, the shoe being rigidly held in position at one end thereof by the hook 42 and at its opposite end by the staple 43. At the same time, the shoe may be readily detached by simply removing the bolt 44. The shoe is, of course, curved to conform to the curvature of the wheel 11 and is arranged to engage said wheel at its upper side, being normally supported out of contact with the wheel by the hanger 15. Formed on the brake head at its inner end is a pair of ears 45 and pivoted at its outer end between said ears is a thrust rod 46, the inner end of which is rigidly connected with the truck frame. The rod 46 will thus serve to brace the brake head against longitudinal movement under the influence of the drag of the wheel 11 upon the brake shoe.

Having thus described the invention, what is claimed as new is:

1. In brake mechanism, a brake head provided with a transverse opening therethrough and having a recess entering through the lower face of the head to intersect said opening, the head being further provided at one end with a longitudinal recess, a brake shoe seating against the lower face of the head, a hook carried by one end portion of the shoe engaging in the latter recess, a staple carried by the opposite end 100

105

110

- portion of the shoe received in the first recess, and means extending through said opening and through the staple locking the shoe upon the head.
5. 2. In brake mechanism, a brake head having spaced recesses, a brake shoe having spaced means extending into said recesses, one of said means coacting with the head for connecting the shoe thereto, and means extending through the head coacting with another of the first means locking the shoe upon the head.
10. 3. In brake mechanism, a brake head having recesses one extending longitudinally of the head, and a brake shoe seating against the head and provided with means engaging in said longitudinally extending recess and with other means received in the other of said recesses in the head, and means extending through the head coacting with the latter means of the shoe for locking the shoe upon the head.
15. 4. In brake mechanism, a brake head provided with recesses one entering through one end face of the head and the other entering through a longitudinal face of the head, a brake shoe having a hook engaging in the first recess and provided with a staple received in a second recess, and means extending through the head and said staple locking the shoe upon the head. 25
5. In brake mechanism, a brake head provided with recesses one entering through an end face of the head and the other through a longitudinal face of the head, a brake shoe 35 having a hook engaging in the first recess and provided with a staple received in the second recess, lugs upon the shoe coacting with the ends of the head, and means extending through the head and said staple 40 locking the shoe upon the head.

In testimony whereof I affix my signature.

GEORGE L. SCOTT. [L.S.]
